UNITED STATES PATENT OFFICE

EDWARD H. RADECKY, OF DETROIT, MICHIGAN, ASSIGNOR TO THE MURRAY CORPORATION OF AMERICA, A CORPORATION OF DELAWARE

MUFFLER FOR INTERNAL COMBUSTION ENGINES

Application filed May 18, 1929. Serial No. 364,136.

An object of my invention is to provide a muffler for an internal combustion engine which is cheap to manufacture, and simply assembled, and in which the parts are all rigidly held against working loose and rattling.

Another object of my invention is to provide such a muffler composed of substantially uniform parts throughout.

Another object of my invention is to provide a muffler for an internal combustion engine which is divided into substantially three compartments comprising an intake compartment and an outlet compartment, and an ultimate expansion and cooling compartment surrounding both said intake and outlet compartment and communicating with each of them.

Another object of my invention is to provide a muffler comprising three concentrically arranged tubes in which the two inner tubes are separated by baffles into inlet and outlet compartments and in which the outer tube surrounds the inner tubes and forms a communicating path between them and in which the flow of gases from the inlet to the outlet compartment are controlled by the area of passages between the inlet compartment and the outer tube and between the outer tube and the outlet compartment, the total area of passages between the outer tube and the outlet compartment being slightly less than the total area of passages between the inlet compartment and the outer tube, whereby the reduction in volume of gases by cooling and condensation is compensated for and sufficient pressure is maintained in the outlet compartment to effectively offset the tendency of air to rush into the muffler through the outlet pipe when the engine is decelerated, and thereby eliminate drumming when the volume of exhaust gas from the engine is suddenly diminished.

With these and other objects in view, my invention consists in the arrangement, combination and construction of the various parts of my improved device, as described in the specification, claimed in my claim, and shown in the accompanying drawing, in which:

Fig. 1 is a longitudinal cross section of my

muffler having parts broken away to illustrate the construction of the various parts.

Fig. 2 is a view taken on the line 2—2 of Fig. 1.

Fig. 3 is a view taken on the line 3—3 of Fig. 1.

The muffler comprises three concentric tubes 10, 11 and 12, 10 being the outer tube or casing, 11 being the intermediate tube, and 12 being the inner tube. Head pieces 13 are provided for each end of the muffler and comprise plates having lateral shoulders formed thereon adapted to support the ends of the tubes in spaced concentric relation to each other. The head pieces 13, one of which is applied to each end of the muffler may be identical and are provided with central openings in which the engine exhaust pipe 14 and the tail pipe 15 may be secured. The tubes 10, 11 and 12 each extend the full length of the muffler, although they are of different lengths in order to fit the shoulders on the head pieces 13. Intermediate the ends of the muffler the inner tube 12 is divided into two compartments of substantially equal capacity by the circular baffle 16, which is a concave plate having lateral flanges formed thereon which are attached to the sides of the tube 12 by welding or other suitable means. The intermediate tube 11 is also divided into two compartments by the baffle plate 17 which comprises a circular plate having a central opening of the proper size to fit closely around the outside diameter of the inner tube 12. Around this central opening in the baffle 17 is formed a lateral flange 18 which is welded to the outside of the inner tube 12 at a point opposite the position of the lateral attaching flange on the baffle plate 16 which is secured to the inside of the tube 12. The outer edge of the baffle 17 is also formed with a laterally extending flange 19 which is secured by a press fit or other suitable means to the wall of the intermediate tube 11. All of the tubes 10, 11 and 12 are secured at their ends to the head pieces 13 and the exhaust pipe 14 is suitably secured in the central opening in the inlet head. The tail pipe 15 is likewise secured in the central opening of the outlet head piece 13, or may be formed as an

integral part thereof when the piece is drawn.

A plurality of holes are formed in the inner tube 12 and in the intermediate tube 11 on the left or inlet side of the baffles 16 and 17. On the right or outlet side of the baffles 16 and 17 a plurality of holes are formed in the intermediate tube 11 and likewise a plurality are formed in the inner tube 12. However, the total area of the holes in this right end of the tube 11 are slightly less than the total area of the holes in the left end of the tube 11, and the total area of the holes in the tube 12 to the right of the baffle 16 is slightly less than the total area of the holes in the right end of the tube 11. However, this arrangement may be varied to suit conditions so long as the total area of the holes or passages in the right or outlet ends of tubes 11 and 12 are less than the total area of the holes in the inlet ends.

Gas entering through the exhaust pipe 14 strikes the left or concave side of the baffle 16 and passes through the holes in the left end of the tube 12 into the left end of the tube 11 and through the holes therein into the outer tube 10. The gas, during this process, is expanded, and when it passes into the outer tube 10, which, owing to its direct contact with the air is generally cooler than either of the tubes 11 or 12, will effect a cooling of the exhaust gases and a slight condensation and slowing up of expansion, and the reduction of the area of the passages leading from the outer tube 10 through the right end of the intermediate tube 11, and the right end of the intermediate tube 12, will cause a sufficient back pressure in the outer tube 10 and in the inlet ends of the tubes 11 and 12 to deaden the impulses of incoming gas, and will also build up a sufficient pressure to provide a comparatively steady flow of exhaust gas from the outer tube 10 into the right or outlet ends of the tubes 11 and 12, which will continue for a short interval after the deceleration of the engine, and will thus provide a steady pressure in the outlet end of the muffler which will tend to prevent the formation of a low pressure area within the muffler upon deceleration of the engine, which would cause air to rush into the muffler and produce an unpleasant drumming sound. The construction, comprising the three tubes rigidly supported by common end pieces, with the rigidly secured internal baffle plates, has no parts likely to work loose and rattle; and the device in actual use proves to be an efficient silencer and does not build up back pressure to a degree which materially affects the operation of the engine. It is also, on account of the uniformity and small number of parts, cheap to produce.

Formal changes may be made in the specific embodiment of the invention described without departing from the spirit or substance of the broad invention, the scope of

which is commensurate with the appended claim.

What I claim is:

A muffler for an internal combustion engine comprising three tubes arranged in spaced concentric relation to each other, a pair of head pieces supporting the ends of said tubes and having central openings leading to each end of the inner tube, baffle plates secured intermediate the ends of the inner and intermediate tubes and dividing each of them into two chambers of substantially equal capacity, said inner and intermediate tubes having lateral passages therethrough on the inlet side of said baffle plates, and said intermediate tube having lateral passages on the outlet side of said baffle plates of lesser area than on the inlet side, and said inner tube having lateral passages on the outlet side of lesser total area than the corresponding passages in said intermediate tube.

EDWARD H. RADECKY.
